UNITED STATES PATENT OFFICE.

ZENONAS L. LITVINAS, OF CHICAGO, ILLINOIS.

TAILSTOCK FOR MULTIPLE-SPINDLE LATHES.

Application filed December 17, 1921. Serial No. 523,139.

To all whom it may concern:

Be it known that I, ZENONAS L. LITVINAS, a citizen of Lithuania, residing at Chicago, county of Cook and State of Illinois, have 5 invented certain new and useful Improvements in Tailstock for Multiple-Spindle Lathes, of which the following is a specification.

This invention relates to an improvement 10 in multiple spindle lathes, and is directed particularly to means for securing the tail stock spindles in adjusted positions for holding the centers.

The invention is illustrated in the accompanying drawings, in which:

Fig. 1 is a view in broken elevation showing a portion of a multiple spindle lathe, with the improvement applied thereto.

Fig. 2 is a vertical section through the 20 tail stock.

Fig. 3 is a section on line 3—3 of Fig. 2, the locking means being shown in elevation.

In the drawings, the tail stock 1 is mounted upon the bed in the usual manner, and 25 provision is made for supporting a plurality of work pieces, as 2 and 3, thereby.

The centers 4 and 5 have the usual pointed ends 6 to cooperate with the work pieces, these centers being mounted in tail stock 30 spindles 7 and 8, having channels 9 to slidably receive pins 10 adapted to engage the centers at one end and provided at the opposite end with enlargements 11, to be engaged by rods 12 threaded in the spindles.

The rods are provided with collars 13 to 35 prevent endwise movement in one direction and extended through the tail stock and provided on their free ends with hand wheels 14 for convenient rotation of the rods. Obviously, by proper manipulation of the rods, the centers may be accurately positioned to support the work pieces.

The locking device for holding the spindles comprises bolts 15, slidably mounted 40 in a channel 16 extending vertically of the tail stock and opening into the spindle receiving bores. This channel is interrupted at its mid-length by a transverse channel 17, which opens through one side wall of the tail stock. In the channel 17 an adjusting 45 member is arranged in the form of a conical

element 18, in which is threaded a rod 19 which extends through the side wall of the tail stock and is provided with an adjusting wheel 20. The reduced terminal of the conical element 18 has a collar 21 slidably fitting the channel 17 and between this collar and a closing piece 22 for the end of the channel is arranged a coil spring 23 serving to assist in feeding the conical element in 60 one direction.

The ends of the bolts 15 bear against the spindles 7 and 8 respectively, and it is obvious that by adjusting the conical element 18 in one direction, these bolts will be caused 65 to frictionally engage and lock the spindles, the opposite movement of the conical element freeing the frictional lock.

What I claim as new and desire to secure by Letters Patent of the United States is— 70

1. In a multiple spindle lathe, a tail stock having spindles, centers carried thereby for engaging the work, threaded bolts for adjusting said centers, hand wheels for operating the bolts, latches for engaging the 75 spindles, a cone for operating the latches to lock the spindles, and means for operating the cone.

2. In a multiple spindle lathe, a tail stock, a plurality of spindles mounted therein, centers carried by said spindles to engage the work, means for operating the spindles to adjust said centers toward the work, and means for simultaneously locking said 85 spindles in adjusted positions.

3. In a multiple lathe, a tail stock, a plurality of spindles operative therein, centers carried by the spindles for engaging the work, means for adjusting the spindles longitudinally of the tail stock, latches operative transversely of the tail stock and adapted to frictionally engage the respective spindles, a cone arranged transversely of the latches and between the adjacent ends of the same, and means for operating the cone transversely of the latches to cause 90 said latches to frictionally engage and secure the spindles in fixed relation to the tail stock.

In testimony whereof I have affixed my 100 signature.

ZENONAS L. LITVINAS.
